J. A. SEEDE

ELECTRIC FURNACE APPARATUS AND METHOD OF OPERATING THE SAME

Filed May 8, 1916

Inventor:
John A. Seeds,
by *Albert S. Davis*
His Attorney.

UNITED STATES PATENT OFFICE.

JOHN A. SEEDE, OF SCHENECTADY, NEW YORK, ASSIGNEE TO GENERAL ELECTRIC COMPANY, A CORPORATION OF NEW YORK.

ELECTRIC FURNACE APPARATUS AND METHOD OF OPERATING THE SAME.

Application filed May 8, 1916. Serial No. 98,047.

To all whom it may concern:

Be it known that I, JOHN A. SEEDE, a citizen of the United States, residing at Schenectady, county of Schenectady, State 5 of New York, have invented certain new and useful Improvements in Electric Furnace Apparatus and Methods of Operating the Same, of which the following is a specification.

10 When an electric arc furnace operated with alternating current is charged with unfused iron or steel, considerable difficulty sometimes is experienced, particularly in large furnaces, to get enough energy into the furnace at starting to melt the charge. This difficulty is caused very largely by the magnetization of the charge and the consequent reactance introduced into the supply circuit. For example, with a 15-ton furnace supplied with 20 energy at 17,300 amperes at 100 volts, 60 cycles, the reactance during the melting operation may be so high that it would be difficult to get more than about 1,500 kilowatts into the furnace.

25 In accordance with my present invention, this difficulty is overcome by increasing the length of the arc and either increasing the operating voltage or decreasing the reactivity of the circuit during the melting period 30 when the reactance of the charge is high. The voltage of the energy supply may be increased in any way to enable a longer arc to be maintained, for example, by shifting the transformer connections. My invention 35 in one of its aspects comprises a furnace connected to a transformer provided with means for varying the operating voltage.

40 The accompanying drawing illustrates diagrammatically an apparatus for carrying out my invention by changing the connections of the primary windings of the supply transformer.

The drawing shows in section an arc furnace comprising a container 1, in which a charge 2 of iron or steel scrap, or the like, is being melted, the heat being generated by arcs between the charge and the electrodes 3, 4 and 5, respectively. As indicated in the drawing, the electrodes tend to 45 melt shafts or holes into the charge before the entire mass becomes molten and to become surrounded by the unfused charge. The magnetic material, therefore, is magnetized by the current and exercises a 50 choking effect on the current so that it is

difficult to get enough energy into the furnace to melt the rest of the charge during a period short enough for commercial operation.

In the supply system illustrated, the electrode supply conductors 6, 7 and 8 are connected to a transformer having primary windings 8', 9, 10, and secondary windings 11, 12, 13, the latter being normally fixedly connected to the electrodes as the conductors 65 are very heavy and hence not easily rearranged by switching. In the example shown the secondary coils are shown as connected in delta but some other connection may be used.

An electric arc furnace charged with iron or steel is operated ordinarily with an arc about one inch in length consuming about 60 volts. In order to get sufficient energy into the furnace to overcome the starting 75 difficulties above noted, I prefer to operate with a longer arc and a materially higher voltage, for example, an arc about three inches long, and consuming about 100 volts.

The increase in operating voltage may be 80 obtained by connecting the primary coils in delta by moving switches 14, 15, 16 to the left thereby connecting conductors 17, 18, to each other at the contacts 19, 20, conductors 21 and 22 at contacts 23, 24, and 85 the conductors 25, 26, at the contacts 27, 28. Electric energy is supplied through the conductors 29, 30, 31 from a three-phase system 32 of suitable current and voltage. The switches mentioned together with a switch 90 33 may all be connected to a rod 34 and moved in unison thereby.

When the charge has been melted, and the long arc begins to send too much heat to the side walls and roof of the furnace, the arc 95 may to advantage be shortened to operate with a voltage drop of about 60 volts. The connections are shifted to Y, or star, by moving the switch 34 to the right, thereby connecting the conductors 17, 18 and 21 to a 100 common point by the switch 33 at the contacts 35 and connecting the opposite ends of each coil 8', 9 and 10 to the different phases of the supply system by conductors 25, 26 and 22 respectively, at the switch contacts 37, 38 and 36. This Y connection decreases the secondary voltage causing the input of a lesser amount of energy into the furnace.

105 It may sometimes be desirable to operate 110

with a short arc for a period at the very beginning of the operation, and then lengthen the arc while maintaining the current value. In this event the primary windings are connected first in Y, then when the electrodes have penetrated the charge, and have developed a satisfactory arcing surface on the charge, the transformer connections are shifted to delta and the arc lengthened. Finally when the charge has been largely melted, the connections are restored to Y and the arc is shortened to the normal length.

Other methods of increasing the voltage to increase the energy consumed in the arc to overcome the choking effect on the supply current of a magnetized charge in the furnace, may be used within the scope of my invention. For example, the reactivity of the energy supply may be decreased by decreasing the periodicity of the current, or by changing the wave shape and thus minimizing the energy reducing the effect of the reactance.

What I claim as new and desire to secure by Letters Patent of the United States, is,—

1. The method of operating an electric arc furnace supplied with alternating current which consists in first operating the furnace with a short arc, thereupon increasing the length of arc while maintaining the current value, and finally reducing the length of arc to operate with a lower energy input.

2. The combination of an electric furnace, a three-phase transformer having secondary windings fixedly connected to the electrodes of said furnace, and means for connecting

the primary windings of the transformer at will either in delta or star.

3. The combination of an electric arc furnace, a polyphase transformer having secondary windings fixedly connected to the electrodes of said furnace, and means for changing the arrangement of the primary windings to vary the secondary voltage of the transformer.

4. The combination of an electric arc furnace having a plurality of electrodes, a transformer, normally fixed electric connections between the secondary of said transformer and said electrodes, and means for changing the arrangement of the primary windings of said transformer to vary the voltage impressed on the furnace electrodes.

5. The combination of an electric arc furnace having a plurality of electrodes, transformer secondary windings normally connected fixedly to said electrodes, primary windings inductively related to said secondary windings and means for changing the arrangement of said primary windings from delta to star or star to delta.

6. The combination of an electric arc furnace having a plurality of electrodes, a set of transformer secondary coils connected to said electrodes, a set of corresponding primary transformer windings, and means for changing the arrangement of one of said sets of windings while maintaining the electrical connections of the other set intact.

In witness whereof, I have hereunto set my hand this 6th day of May, 1916.

JOHN A. SEEDE.
